(57) **CLAIM**

We claim the ornamental design for an electronics enclosure, as shown and described.

DESCRIPTION

FIG. 1 is a perspective view showing a top, front, and left side of our new design for the electronics enclosure;

FIG. 2 is a perspective view showing a bottom, rear, and right side of our new design for the electronics enclosure; FIG. 3 is a front elevational view thereof, which is identical to the rear elevational view;

FIG. 4 is a right elevational view thereof, being an identical to the left elevational view;

FIG. 5 is a bottom view thereof; and,

FIG. 6 is a top view thereof.
